DEVICE FOR AUTOMATIC RE-SETTING OF TELE-WRITER TO LETTER-PRINTING POSITION

Karel Weber and Jaroslav Váňa, Hradec Králové, Czechoslovakia, assignors to Tesla, národní podnik, Prague, Czechoslovakia

Filed Oct. 13, 1958, Ser. No. 766,757

1 Claim. (Cl. 178—23)

This invention relates to a device for the automatic re-setting of a tele-writer to its letter-printing position, the device comprising two control contacts which are mechanically operated by the tele-writer type wheel and which are connected in the control circuit of an electromagnet which is arranged to switch the type wheel from the position in which letters are printed to the position corresponding to the printing of numbers and marks. The outstanding feature of a device illustratively embodying the principles of this invention resides in the fact that a tele-writer with which such a device is combined operates smoothly and without undue troubles and errors, which in present tele-writer systems in which the initial position of the type wheel is not exactly defined.

When a tele-writer is started by manual or automatic means or when communication is initiated by direct interconnection of two tele-writers, either a letter or a number or a mark is printed as soon as the driving motor and the mechanical controlling members start to move. Additionally, there is another drawback inherent in present tele-writers, namely, that due to the different operating positions of two machines at the instant when communication therebetween is initiated. For instance, the local machine may be set to print letters, whereas the distant one is set to print numbers and marks.

The above-specified drawbacks of known tele-writers may lead to errors therein and, as a result, cause the lowering of the speed of communication due to the necessity of repeating the transmission of information.

The basis of the shortcomings mentioned above lies in the fact that line-current for the tele-writer receiving magnet as well as source voltage for the tele-writer motor is cut off as soon as actual communication of the tele-writer is stopped. The dropping electromagnet and the decelerating motor, however, still actuate some members of the tele-writer control system. When the tele-writer is again started, the source voltage is applied to the driving motor and the receiving electromagnet is energized by the line-current. Therefore, some control members are again actuated until the "Stop" position of all elements is reached. This intermediate state of operation causes erroneous prints.

The device to which the present invention relates gets rid of the above mentioned shortcomings, whereby, when starting a tele-writer by manual or automatic means or by means of a direct interconnection between two tele-writers, the machines are automatically re-set to their letter-printing positions.

In both terminal positions of the type wheel of an illustrative embodiment of the principles of the present invention, i.e., in the position corresponding to the printing of letters and in that corresponding to the printing of numbers and marks, one of two controlling contacts is active, each of these two contacts being used for switching over the type wheel from one position to the other. The embodiment also includes an electromagnet and a control circuit therefor including two branches. In both branches of the electromagnet control circuit contacts of storage relays are connected. When the tele-writer is started, relays for the reception of pulse combinations send equal current pulses to all storage relays (this being equivalent to the letter symbol). If the type wheel finds

2

itself in the position for letter printing, its corresponding control contact in the electromagnet circuit is therefore open, the electromagnet cannot be energized and the type wheel remains in the letter-printing position. On the contrary, if the initial position of the type wheel corresponds to the number printing position, the respective control contact is closed, the electromagnet is energized and switches the type wheel over into the position for letter printing.

10 The above and other advantages and features of the present invention will be better understood from a consideration of the detailed description of a specific illustrative embodiment thereof presented hereinbelow in conjunction with the accompanying drawing, in which:

15 FIG. 1 is a diagrammatic showing of the reception control portion of a tele-writer;

18 FIG. 2 is a diagrammatic showing of the storage control portion of a tele-writer; and

20 FIG. 3 is a diagrammatic showing of an automatic re-setting arrangement illustratively embodying the principles of the present invention.

25 The showing of FIG. 3 of the drawing comprises an electromagnet M and a control circuit therefor, which electromagnet actuates a mechanism in a tele-writer for

28 switching over the type wheel thereof from the letter printing position to the position for printing numbers and marks, and vice versa. The control circuit comprises two branches which respectively include contacts I and II. In FIG. 3, both these contacts are shown enclosed within

30 a dashed-line box. The control circuit also includes contacts a_2 , d_2 , c_1 and b_2 , while in the first branch the contact e_2 (and I) and in the second one the contact e_3 (and II) are connected. All of the contacts a_2 , b_2 , c_1 , d_2 and e_2 and e_3 belong to the storage relays

35 $\begin{matrix} A & B & C & D & E \\ \hline \frac{1}{2} & \frac{1}{2} & \frac{1}{2} & \frac{1}{2} & \frac{1}{2} \end{matrix}$

(FIG. 2) which receive pulses from relays

40 $\begin{matrix} H & I & J & K & L \\ \hline \frac{1}{2} & \frac{1}{2} & \frac{1}{2} & \frac{1}{2} & \frac{1}{2} \end{matrix}$

45 (FIG. 1) these latter relays being designed to receive pulse combinations. In FIG. 1, a reception mechanism RPK, in co-operation with a polarized telephone relay

48 $\begin{matrix} PR \\ \hline 1 \end{matrix}$

50 (having a contact pr_1 , provides for the proper allocation of pulses to the relays

55 $\begin{matrix} H & I & J & K & L \\ \hline \frac{1}{2} & \frac{1}{2} & \frac{1}{2} & \frac{1}{2} & \frac{1}{2} \end{matrix}$

58 In the off position of the tele-writer the reception relay

60 $\begin{matrix} PR \\ \hline 1 \end{matrix}$

63 is de-energized and its armature assumes the position AT. The relays

65 $\begin{matrix} H & I & J & K & L \\ \hline \frac{1}{2} & \frac{1}{2} & \frac{1}{2} & \frac{1}{2} & \frac{1}{2} \end{matrix}$

68 and

70 $\begin{matrix} A & B & C & D & E \\ \hline \frac{1}{2} & \frac{1}{2} & \frac{1}{2} & \frac{1}{2} & \frac{1}{2} \end{matrix}$

75 are de-energized as well, since in that condition of the tele-writer no voltage is applied to the windings of these relays.

78 Now, when the tele-writer is switched on, the reception relay

80 $\begin{matrix} PR \\ \hline 1 \end{matrix}$

gets immediately exposed to the action of line-current and its armature is thrown over into the position AZ. A starting motor brings the mechanism RIPK (that might have been in any arbitrary position) to the "Stop" position. Thereby some of the reception relays

$$\frac{H}{2}, \frac{I}{2}, \frac{J}{2}, \frac{K}{2}, \frac{L}{2}$$

may be actuated, but they get immediately de-energized, 10 since the positive pole from the relay

$$\frac{PR}{1}$$

and the contact OK of the mechanism RIPK are disconnected. Thereby, the releasing reception relays transmit the letter symbol (all five current pulses) over the contacts

$$\frac{h}{2}, \frac{i}{2}, \frac{j}{2}, \frac{k}{2}, \frac{l}{2}$$

the storage relays

$$\frac{A}{2}, \frac{B}{2}, \frac{C}{2}, \frac{D}{2}, \frac{E}{2}$$

The storage relays are, therefore, actuated, their associated contacts are closed and, as seen in FIG. 3, according to the position of the contacts I and II, the electromagnet M either is energized or remains de-energized. As stated above, the electromagnet M serves to mechanically switch the type wheel of the tele-writer from its letter-printing position to its numbers and marks position, or vice versa.

The device according to the present invention causes, therefore, the type wheel to remain in the letter position after the tele-writer has been started in case the initial position of the type wheel was the letter-printing position.

This is because the contact I remains, in that position of the type wheel, open, so that even when all of the relays

$$\frac{A}{2}, \frac{B}{2}, \frac{C}{2}, \frac{D}{2}, \frac{E}{2}$$

are energized, the electromagnet M receives no current. If, on the other hand the initial position of the type-wheel was that corresponding to number and mark printing, the contact I is closed and as soon as the tele-writer has been started, the type wheel is automatically switched over by the electromagnet M into the position for letter printing.

What we claim is:

In combination in a tele-writer of the type which may be either in a letter-printing or a number- and mark-printing condition, electromagnet means for switching the tele-writer between the two conditions, relay means, circuit means for energizing said electromagnet means, said circuit means including switching means and contact members, said contact members being controlled by said 15 relay means, said switching means being in an open-circuit position when the tele-writer is in its letter-printing condition and being in a closed-circuit position when the tele-writer is in its number- and mark-printing condition, and means responsive to the turning on of the tele-writer 20 for energizing said relay means, thereby causing said contact members to be actuated and, if said switching means is initially in a closed-circuit position, causing said electromagnet means to be energized to switch the tele-writer to its letter-printing condition and, if said switching 25 means is initially in an open-circuit position, not causing said electromagnet means to be energized thereby leaving the tele-writer in its letter-printing condition.
